ILLUMINABLE DESK SET

Norman T. McFarland, Urbana, Ill., assignor to Marvin Glass & Associates, Chicago, Ill., a partnership

Filed May 1, 1968, Ser. No. 11,738

Term of patent 14 years

Int. Cl. D19—02; D26—99
U.S. Cl. D74—5

FIGURE 1 is a perspective view of an illuminable desk set showing my new design;

FIGURE 2 is a front elevational view thereof;

FIGURE 3 is a top plan view;

FIGURE 4 is a bottom plan view;

FIGURE 5 is an end view as seen from the left of FIGURE 2; and

FIGURE 6 is an end view as seen from the right of FIGURE 2.

I claim:

The ornamental design for an illuminable desk set, substantially as shown.
